UNITED STATES PATENT OFFICE.

JOHN HAY, OF JUNCTION CITY, KANSAS.

WATER-WHEEL.

1,149,260.

Specification of Letters Patent. Patented Aug. 10, 1915.

Application filed September 16, 1912. Serial No. 720,658.

To all whom it may concern:

Be it known that I, JOHN HAY, a citizen of the United States, residing at Junction City, in the county of Geary and State of Kansas, have invented certain new and useful Improvements in Water-Wheels; and I do hereby declare the following to be a full, clear, and exact description of the invention, such as will enable others skilled in the art to which it appertains to make and use the same.

This invention is a water wheel of the type which is vertically adjustable for the purpose of adapting the wheel to various changes in the level of the water by which it is driven.

Where the banks of a stream are low and high dams cannot be erected economically, it has been a difficult problem to utilize the power of shallow streams for turning water wheels which operate motors.

A purpose of this invention is to utilize the flow of a stream of water under various conditions, and obtaining power therefrom when the water is shallow as well as when it is deep, thereby attaining results substantially the equivalent of deepening the water of a shallow stream.

A further purpose of the invention is to retain the wheel submerged, or partly submerged, at various depths, and thereby increase or diminish the power of the wheel.

Further objects and purposes of the invention will become apparent from the following detail description.

The invention contemplates the mounting of a wheel on a sluiceway in such a manner that the power of the water flowing through the sluiceway will be directed upon one side of the wheel only and thereby increase the power of the motor.

The invention consists, also, in means for guiding the vertical movement of the wheel with reference to the sluiceway, in manually operated means for raising and lowering the wheel with reference to the sluiceway, as well as counterbalancing members serving to retain the wheel in a desired position.

In the accompanying drawings, one embodiment of the invention is illustrated, but the construction shown therein is to be understood as illustrative only and not as defining the limits of the invention.

Figure 1 is a vertical sectional view through a sluiceway showing the wheel in position at the bottom thereof. Fig. 2 is a

horizontal sectional view illustrating the position of the counterbalancing means with reference to the wheel. Fig. 3 is a detailed view of the elevating and counterbalancing means.

The water wheel 5 may be of any preferred construction and in the drawings is shown provided with upper and lower disks 6, 7, and with curved blades 8 connecting said disks. The blades 8 extend from the peripheries of said disks inwardly toward a shaft 9, to which the wheel may be connected in any suitable manner, as at 10. This water wheel 5 is shown arranged in a sluiceway 11, having a plurality of deflectors 12 and 13 which operate to cause the full force of the water to be exerted upon one side of the wheel, with substantially none of the energy of the water affecting the other, or negative, side of the wheel.

The wheel is adapted to slide up and down with reference to the shaft, the lower end of the shaft 9 being stepped at 14, while the upper end thereof is provided with a sleeve 15 having a flange 15^a positioned above an upper support 16. The flange 15^a and support 16 may be provided with a race for ball or roller bearings. Power is transmitted from the shaft 9 to other forms of machinery by any suitable means, as by gear 9^a. A lower horizontal supporting member 17, upon which the wheel 5 rests, is also slidably mounted upon a vertical shaft. Upon each side of the sluiceway is provided a boxing 18 for the reception of counterbalancing weights 19 and a portion of the elevating mechanism. An end of the base supporting member 17 extends into each of these boxings 18, as shown in Fig. 2. To the two protruding ends of the supporting member are attached one end of an elevating chain or cable 20. Each cable or chain extends upwardly from the supports 17, passes over a wheel, such as a sprocket wheel 21, which may be positioned above the upper supporting member 16, said cable thence extending downwardly to the counterbalancing weights 19. The weights 19 are provided with an eye 22 to which the chain 20 is to be attached, and also with a horizontal weight supporting rod 23 having upturned ends 24. Additional weights 25 may be removably mounted upon these rods 23, as may be required in the operation of the wheel, for example, to cause the water wheel to be raised by gravity.

Suitably mounted upon the upper end of the sluiceway, or the boxing, as may be preferred, are brackets 26, coöperating with side braces 27, which serve to support a horizontal shaft 28, having crank arms 29 for rotating the shaft. The sprocket wheels 21 are secured to this shaft for rotation therewith, and the shaft is further provided with a ratchet wheel 30 adjacent to each sprocket wheel 21. A pawl 31, pivotally mounted at a suitable place adjacent the ratchet, operates to retain the parts in position when the water wheel 5 is being raised or lowered by the manually operating means 29. When the water wheel is to be raised by gravity means 19, 25, the pawl 31 is disengaged from the ratchet, as will be readily understood.

Should there be considerable water in a stream, the water wheel may be raised to the proper elevation by manipulating the crank arms 29, which will raise the horizontal base member 17, carrying the wheel 5, by means of the chains 20 passing over the sprocket wheels 21. Should the water be very low in the stream, the water wheel could be lowered to the bottom of the sluiceway by the manually operated means or by gravity. However, it is preferred to make the weights 19 substantially equal to the weight of the water wheel, and to utilize the weights 25 for the purpose of raising the wheel by gravity, when the water wheel is at its lowermost position.

Having thus fully described my invention what I claim as new and desire to secure by Letters Patent is:—

1. In a device of the class described, a frame, a vertical shaft rotatively mounted in fixed relation thereto, a lower horizontal member slidable vertically on said shaft, a water wheel carried by said shaft and movable vertically with reference thereto, a horizontal shaft mounted on said frame above said water wheel, sprocket wheels carried by said horizontal shaft, means for rotating said horizontal shaft, and a flexible member connecting said lower horizontal member and said sprocket wheel, whereby said lower horizontal member and the wheel

may be retained at various positions with relation to the shaft.

2. In a device of the class described, a frame, a vertical shaft rotatably mounted in fixed relation thereto, a lower horizontal member slidable vertically on said shaft, a water wheel carried by said shaft and movable vertically with reference thereto, a horizontal shaft above said water wheel, sprocket wheels carried by said horizontal shaft, a plurality of counterweights, a housing guide for said counterweights, and flexible members engaging said sprocket wheels and connected at one end to said counterweights and at the other end to said lower horizontal member.

3. In a device of the class described, a frame, a vertical shaft carried thereby, a lower horizontal member engaging said shaft, a water wheel carried by said shaft and movable vertically with reference thereto, a horizontal shaft mounted above said water wheel and provided with crank arms, sprocket wheels carried by said shaft, means for retaining said sprocket wheels in fixed relation to said shaft, a plurality of counterweights, and flexible members engaging said sprocket wheels and connecting said counterweights to said lower horizontal member.

4. In a device of the class described, a frame, a vertical shaft fixedly mounted to rotate in said frame, a bearing at the base of said frame, said shaft being stepped in said bearing, means secured to the upper end of said shaft to maintain it in fixed vertical position on the frame, and to form a bearing for the shaft, and a water wheel carried by said inner frame and adjustable vertically on the shaft, said bearings serving to maintain the shaft in rigid vertical position irrespective of the position of the water wheel thereon.

In testimony whereof, I affix my signature, in presence of two witnesses.

JOHN HAY.
